CLAIM

The ornamental design for electro-optical watch dial or the like, as shown.

DESCRIPTION

FIG. 1 is front elevational view of electro-optical watch dial showing my new design and indicating the time to be approximately seven minutes before three o'clock;

FIG. 2 is a similar front elevational view showing the time to be three o'clock;

FIG. 3 is a similar front elevational view showing the time to be approximately five minutes after ten o'clock;

FIG. 4 is a similar front elevational view showing the time to be approximately six minutes after one o'clock;

FIG. 5 is a rear elevational view thereof; and

FIG. 6 is a typical side view thereof.

FIG.1
